Application December 3, 1936, Serial No. 114,037

21 Claims. (Cl. 132—33)

This invention relates to a method of and apparatus for permanently waving hair. An object of the invention is to provide a process whereby a flat strand of hair may be wound on a mandrel, beginning at an intermediate portion of the strand and winding a distal portion first, progressing toward the distal end of the strand, while maintaining the strand in flat condition and thereafter winding up the inner portion of the strand Croquignole fashion, that is, in substantially true spiral form progressing toward the scalp by rotating the winding mandrel and the previously wound hair.

A further object of the invention is to interleaf with a terminal convolution or portion of a convolution, or even with more than a complete terminal convolution, a piece of thin flexible sheet material whereby to facilitate unwinding the strand in the reverse order to that in which it was wound. I have found that difficulties arise when it is attempted to unwind the first portion by simply rotating the mandrel in the same way as in unwinding the portion of the strand which was wound Croquignole fashion, although this method of unwinding may be sufficiently successful when the strand is not maintained flat. By interleaving with a terminal portion of the strand, a piece of cheese cloth or the like, I am able to unwind the strand after the wave has been produced without difficulty.

I have found that for best results in Croquignole winding, it is desirable to wind on a spool which tapers from the ends toward the center. Inasmuch as a portion of the strand, according to the present method, is to be wound Croquignole fashion, I prefer to wind the distal portion of the strand in such manner that it may form with the curler rod a spool of such configuration. I also desire to avoid any abrupt bends in the hair. Accordingly, it is an object of the invention to wind the first turn upon a curler rod which is provided with a depression of helical shape to receive such first turn, and to wind the remaining turns of the distal portion in such manner as to build up a substantially symmetrical spool or mandrel for the winding of the scalp portion of the strand.

Accordingly, I provide a curler rod of such shape as to accomplish these results, that is, one which is cut away in such manner that when the hair is wound up in the desired shape, a proper winding mandrel composed partly of the curler rod and partly of hair will be presented for winding the inner portion of the strand in Croquignole fashion. The depressed portion of the

curler rod above referred to is also useful in preventing longitudinal slippage of the hair on the curler rod. Providing for such means for preventing slippage of the hair, the provision of a clamp for holding the hair at the beginning of the wind and the provision of a tapered portion to receive the distal portion of the strand and to prevent longitudinal slippage thereof are further objects of the invention.

While it is possible for an operator of great skill to perform the improved process more or less well by the use merely of the curler rod and a comb or similar simple instrument, in the practical application of the invention and in the use thereof by relatively unskilled operators, it is necessary that a winding device be provided for placing the hair on the curler rod. Indeed, it is doubtful whether even an operator of the highest skill would be able without mechanical winding means, to accomplish results as satisfactory as those which I am able to accomplish readily by the use of the winding device herein disclosed.

It is accordingly an object of the invention to produce a novel and superior winding device for laying down the flat hair strand on the novel form of curler rod.

A further object is to provide a winding device wherein superior tensioning is secured, particularly by the employment of a snubbing action.

A further object is to provide a novel relationship between the winding means and the curler rod wherein the former is guided with respect to the latter. This novel relationship comprises the mounting of the winding means on a guide rod which is received within an axial bore in the curler rod, and also, in the provision of means for regulating in a predetermined manner the rotational and longitudinal motion of the winding means with respect to the curler rod in a predetermined relationship whereby to lay down the hair on the curler rod in a predetermined manner.

A still further object is to provide for the use of a curler rod which is longer than the protector clamp in combination with which it is used.

Other and more limited objects will be in part apparent and in part pointed out hereinafter in connection with the accompanying drawings wherein Fig. 1 is a sectional view of the winding means and showing the guide roll thereof received in the guide bore of the novel form of curler rod. This view is taken looking toward the operator of the device. Fig. 2 is a plan view of the winding device shown in Fig. 1, the curler rod being re-

- 5 moved. Fig. 3 is an end view of the winding device with the curler rod removed and showing the clamping portions of the winding device separated for receiving a strand of hair to be wound.
- 10 5 Fig. 4 is a view similar to Fig. 3 but showing the clamping elements and the tensioning means in clamping position and indicating by dot and dash lines the strand of hair passing through such tensioning means and between the teeth of the 10 comb element which maintains the strand flat and of constant width. Fig. 5 is a schematic view indicating the first turn on the curler rod. It is to be understood that this view indicates the manner of placing the hair whether the same be 15 done manually or by means of the winding device. Fig. 6 is a second schematic view indicating the interleaving of the fabric beneath the last convolution to facilitate unwinding, this view corresponding substantially to a section on the 20 line 6—6 of Fig. 5. Fig. 7 is a schematic view showing the appearance after the distal portion of the hair has been wound up, the fabric interleaved with the last convolution and wound around the curl and the inner portion of the 25 strand on the curler rod Croquignole fashion. Fig. 8 is a schematic plan section showing the protector clamp in plan, the curler rod in section, and the hair wound thereon in dotted outline. This view brings out the relative positions of the 30 portions of the curl which have been wound from the intermediate portion toward the end and the inner or scalp portion which has been wound Croquignole fashion. Fig. 9 is a view similar to Fig. 7 but showing a modified form of the device 35 wherein the curler rod is of a length greater than that of the protector clamp. This form is similar to the preceding form but differs in that it is adapted for waving long hair and makes use of a somewhat different type of protector clamp. Fig. 40 10 is an end view looking from right to left in Figs. 7 and 9 and showing the construction of the protector clamp and its relation to the curler rod. Fig. 11 is an end view looking from left to right in Fig. 9 and showing a special supporting 45 cradle for receiving the wound curl. This varies from conventional structure in that the entire curl including the hair is received in the cradle, instead of the curler rod only. Fig. 12 is a detail view of the flexible strip which is interleaved with 50 the hair strand. Fig. 13 is a view similar to Fig. 1 but looking at the device from the operator's position and showing the guide groove formed in the inner surface of the handle portion of the winding device and the cooperating pin formed 55 on the curler rod and Fig. 14 is a detail view showing the passage between the annular portion of the guide groove and the portion of the inner surface of the handle of the winding device which permits motion without exerting any guiding action further than to prevent escape of the winding 60 device from the curler rod.
- 65 Referring now to the drawings, the numeral 10 indicates generally a curler rod of special construction for cooperation with a winder, indicated generally by the numeral 11, in the performance of the novel process. The curler rod may be provided with the usual ratchet surface as indicated at 12 and may be of the usual length of curler rods employed in Croquignole waving as 70 now generally practiced. As will hereinafter appear, this rod may be of a greater length than the usual Croquignole curler rod and without increasing the length of the protector clamp, by the provision of a special cradle as shown in Figs. 75 9 and 11. Adjacent the ratchet portion 12, the 15 curler rod is provided with a surface 13 which tapers toward the center of the rod and may be a surface of revolution. Farther toward the center of the curler rod, the same may be provided with a surface 14 which may be also a surface of revolution, of similar taper, and closer to the axis of the curler rod by an amount sufficient to accommodate a strand of hair. The surfaces 13 and 14 are joined by a helical abutment 15, which however merges with the surfaces by an easy 20 curve. The surface 14 may be regarded as a depression or cut away portion or as a wide thread extending around the curler rod and having a pitch equal to its width so that one turn 25 serves to end the thread.
- 30 Positioned at the beginning of the abutment 15 and extending in the same direction as the axis of the curler rod is a holding element 16 which may be pivoted, as indicated at 17 at a middle position on the curler rod, about the end of the 35 abutment or thread. This element may be pivoted to a suitable boss 18. Beyond the boss 18 the curler rod may be a substantial surface of revolution and preferably tapers from the end toward the center as clearly indicated at 19. It will be 40 obvious that the surface of the curler rod, as above described and as shown in the drawings, may be regarded as a mutilated curler rod derived from the standard symmetrical Croquignole curler rod which tapers toward the center from both ends 45 and, it will be observed, the shape is such that the first turn of hair substantially restores the standard shape of that end of the curler rod which is adjacent the ratchet portion as seen in the drawings.
- 50 It will also be clear that by winding the first turn parallel to the helical abutment 15 and succeeding turns at a smaller pitch or even in substantially true spiral formation, the other end of the curler rod may be built up into a shape 40 approximating the standard symmetrical curler rod so that the portion of the curler which is wound Croquignole fashion will be wound on a surface approximating that of the standard curler rod. The principal difference, insofar as the 45 Croquignole portion of the wind is concerned, is that the spool, comprising partly the surface of the curler rod and partly the previously wound portion of hair will be somewhat shorter than usual. This however is not objectionable, and in 55 fact, results in a somewhat smoother wind than in the case of the longer spool. Contributing also to the effect of greater smoothness in the Croquignole wind is the fact that the length of the strand which is wound Croquignole fashion is shorter than in normal Croquignole winding.
- 60 As will be observed from the drawings, the curler rod 10 is provided with a central axial bore 20 which receives a guide rod 21 forming a portion of a mechanical winding device. Carried by 65 the rod 21 is a cylindrical handle portion 22 of the winding device which has a central opening 23 adapted to be received over the end of the curler rod 10. Carried by the flange 24 of the winding device 11 is a guiding and tensioning 70 device comprising a rod 25 fixed to the flange 24 and having an upturned end portion 26 and a rotatable element, indicated generally by the numeral 27, and comprising a mounting rod 28 extending through the flange 24 and having an 75 upturned handle 29, an arm 30 carrying a friction element 31 adapted to urge the strand of hair against the rod 25 and a comb element 32 adapted to maintain the strand flat and guide the same between the elements 25 and 31. A spring 75

33 constantly urges the arm 30 in a direction to cause the elements 25 and 31 to grip the strand of hair and to position the comb element in covering relation to the space between the elements 25 and 31, whereby the hair will be accurately guided.

As indicated in Fig. 4 by a dot and dash line, the hair passes from the curler rod 10 to the rod 25 and is bent around the same before passing beneath the friction element 31, which may be composed of rubber. It is thus clear that the surface of the strand which is in contact with the rod 25 will be subjected to a snubbing action while the other surface will be subjected to the friction of the element 31. Thus the two surfaces of the strand may be about equally tensioned. By rotating the winding element in a counter-clockwise direction, referring to Figs. 3 and 4, and moving the same longitudinally, it will be seen that the hair may be placed on the curler rod in the manner indicated in Fig. 5. The rotational and longitudinal motion of the winder may be properly related to each other either by the skill of the operator or by means of guide grooves formed on the inner surface of the element 22 as will be brought out in connection with Figs. 12 and 13.

As hereinbefore indicated, the winding method herein disclosed may be performed more or less satisfactorily by an operator of high skill without the aid of the winding device 11. Accordingly, in Figs. 5 to 8 inclusive, the appearance of the winding at different stages is illustrated without any showing of the winding device. It is to be understood however that the preferred procedure is to place the hair on the curler rod in the manner indicated in those figures by the aid of the winder disclosed in Figs. 1 to 4.

In Fig. 5 I have shown diagrammatically the appearance of the curler rod with one turn of a flat strand placed thereon, the strand being maintained flat and of a substantially uniform width at all points. In Fig. 6 I have shown diagrammatically the approximate appearance in section corresponding to the line 6-6 of Fig. 5 of the strand after the distal portion 34 has been wound to a point where only a short portion thereof remains to be wound up. In this view, I have also shown diagrammatically the introduction of a piece of thin sheet material 35 beneath the last convolution to facilitate unwinding the portions of the strand in the reverse order of winding. After the distal portion 34 of the strand has been wound up, the fabric 35 interleaved therewith and wound up thereon as indicated in Fig. 7 and secured against unwinding as by means of an adhesive patch 36 or any suitable fastening means, the inner or scalp portion 37 of the strand is wound up Croquignole fashion and the curler rod 10 having the hair thus wound thereon is secured to a protector clamp 38 of usual construction, which was secured in clamping relation to the strand before the winding was begun. This protector clamp has the usual clamping jaws 39 and is provided with cradles 40 and 41 for supporting the curler rod. One of the cradles is also provided with a pawl member 42 adapted to cooperate with the ratchet portion 12 of the curler rod.

In Fig. 8, I have illustrated diagrammatically in dotted outline the positions on the curler rod occupied by the distal and scalp portions of the strand. It is to be understood that this is illustrative only and that the precise contour will vary according to the length of the strand and the

variation in the particular manner of positioning the hair adopted by the particular operator.

In Figs. 9 and 11, I have indicated a modified form of protector clamp wherein the cradle 41 is replaced by a cradle 43 adapted to receive the curler rod having hair wound thereon. This permits the use of a slightly modified curler rod 44 varying from that previously described in that the portion thereof upon which the distal portion of the strand is wound has been made longer to accommodate a longer strand of hair.

In Fig. 13, I have shown a modified form of my device, differing from that previously described in that the portion 22 is provided with guide grooves on its inner surface adapted to receive a fixed projection 45 carried by the curler rod. These guide grooves may comprise a helical portion 46 beginning at the point 47 and extending helically around the inner surface of the element 22 and opening into an annular groove 48 which in turn opens by a passage 49 into a wider groove or relieved portion 50. The portion 50 in turn opens by passage 51 to the end of the element 22 whereby the portion 45 may be inserted into starting position. The fragmentary development of Fig. 13 shows the relationship of these passages with the exception of the helical groove 46. It will be noted that the helical groove 46 opens into the inner groove 48 at the point 52 which is 180° spaced from the passages 49 and 51. At the beginning of operation, the winder is placed on the curler rod by registering the passages 51 and 49 with the projection 45, then rotating the winder through 180° to cause the projection 45 to be received in the groove 46, after which it is rotated a full turn to starting position. It is to be understood that the passage 49 need not be positioned at precisely 180° from the point 52. It is desirable however that following the rotation to the point that the projection 45 enters the annular groove 48, a portion of a revolution be wound without substantial motion of the winder toward the end of the curler rod. This rotation of a half, three-quarters or even a full turn serves to bind the helical portion of the strand in firm position on the curler rod. The abutment 15 on the curler rod serves to hold the helically wound turn of the strand against longitudinal motion, then the overlapping of the second part or whole turn with small or no progress toward the end of the curler rod serves to bind a portion of the helical turn to the curler rod and the taper on the small end of the curler tends to prevent longitudinal motion of the wound curl toward that end. After the binding turn or portion of a turn has been taken, the projection 45 may pass into the relieved portion or wide groove 50 whereupon the succeeding convolutions may, if desired progress toward the end of the curler rod. It is within the contemplation of my invention to have the helical groove 46 open immediately into the relieved portion 50 whereby it will rest within the choice of the operator as to how the succeeding convolutions are laid down.

It is to be understood that the pitch of the groove 46 will be the same as that of the abutment 15. In Fig. 12, I have shown in plan the sheet material which is to be interleaved with the last convolution or convolutions or portion of a convolution of the strand. This may take the form of a strip of cheese cloth or the like. Where a flimsy fabric of this kind is used, it is desirable that the same be lightly treated with stiffening material such as latex and that the end which

is first placed in engagement with the hair should be stiffened for a short distance as indicated at 35^a. This may be done by treating it more heavily with latex or by folding a portion and then dipping or otherwise treating it with latex, whereby additional stiffness is imparted thereto.

Inasmuch as Fig. 13 includes all the mechanism of Fig. 1 with the addition of guiding means for accurately laying down the wound strand of hair, it will be more convenient to describe the operation in connection with Fig. 13.

The strand of hair to be wound is first separated in the usual manner and combed out in flat formation as is usual in Croquignole waving. The winder 11 is then engaged with the strand near the scalp, the strand passing between the rod 25 and the gripping element 31 as indicated by the dot-and-dash line in Fig. 4. The strand is then pulled through between the elements 25 and 31 for a short distance after which the curler rod 10 is inserted over the guide rod 21 and extended into the handle of the winder. The curler rod 10 is held in the right hand of the operator while the winder is manipulated with the left hand. The winder is rotated in the direction indicated in Fig. 4 so that the hair is bent over the rod 25 to secure a snubbing action as indicated. The winding is then continued until the hair has been wound up to a point near the end of the strand. At this point the element 35 is interleaved with the convolutions of the hair as indicated in Fig. 6 and the remainder of the strand is wound up. The winder is then removed from the rod and the partially wound strand is wound up manually in the same manner as a Croquignole wind is normally made.

Having thus described my invention, what I claim is:

1. A curler rod having one end portion tapering toward the other end, a portion of the said tapered end portion being defined by a substantial surface of revolution, said surface terminating in a generally helical abutment defining the beginning of a surface generally concentric with said first surface but closer to the center of the rod, the other end portion of said rod being smaller than the first mentioned end portion and tapering toward said first end portion.

2. A curler rod having one end portion tapering toward the other end, a portion of the said tapered end portion being defined by a substantial surface of revolution, said surface terminating in a generally helical abutment defining the beginning of a surface generally concentric with said first surface but closer to the center of the rod, the other end portion of said rod being smaller than the first mentioned end portion.

3. A curler rod having one end portion tapering toward the other end, a portion of the said tapered end portion being defined by a substantial surface of revolution, said surface terminating in a generally helical abutment defining the beginning of a surface generally concentric with said first surface but closer to the center of the rod, the other end portion of said rod being smaller than the first mentioned end portion, and means for holding a flat strand of hair in contact with said rod with an edge of said strand approximately at the junction of said first and second surfaces.

4. A curler rod having one end portion tapering toward the other end, a portion of the said tapered end portion being defined by a substantial surface of revolution, said surface terminating in a generally helical abutment defining the

beginning of a surface generally concentric with said first surface but closer to the center of the rod, the other end portion of said rod being smaller than the first mentioned end portion, being substantially a surface of revolution and tapering toward said first end portion, and means for holding a flat strand of hair in contact with said rod with an edge of said strand approximately at the junction of said first and second surfaces.

5. In combination with a curler rod having a central, axially extending bore, means for winding hair on said curler rod and comprising an open ended handle portion, a guide rod secured to said handle therewith and projecting from the opening therein, said guide rod being adapted to be rotatable and slidably received within said curler rod while said handle portion is received over said curler rod and means carried by said handle portion for tensioning, guiding and maintaining flat a flat strand of hair as it is wound on said curler rod.

6. In combination, a curler rod having a central, axially extending bore, a guide rod rotatably and slidably received in said bore and hair winding means carried by said guide rod and adapted to move around and along said curler rod as said guide rod rotates and slides therein.

7. A curler rod having one end portion tapering toward the other end, a portion of the said tapered end portion being defined by a substantial surface of revolution, said surface terminating in a generally helical abutment defining the beginning of a surface generally concentric with said first surface but closer to the center of the rod, the other end portion of said rod being smaller than the first mentioned end portion, being substantially a surface of revolution and tapering toward said first end portion, said curler rod having a central, axial bore, a guide rod rotatable and slidable in said bore and hair winding means carried by said guide rod and adapted to move around and along said curler rod as said guide rod rotates and slides therein.

8. A curler rod having one end portion tapering toward the other end, a portion of the said tapered end portion being defined by a substantial surface of revolution, said surface terminating in a generally helical abutment defining the beginning of a surface generally concentric with said first surface but closer to the center of the rod, the other end portion of said rod being smaller than the first mentioned end portion, and being substantially a surface of revolution, said curler rod having a central, axial bore, a guide rod rotatable and slidable in said bore and hair winding means carried by said guide rod and adapted to move around and along said curler rod as said guide rod rotates and slides therein.

9. Permanent waving process including the steps of gripping a strand of hair adjacent the scalp, holding a curler rod transversely of and in contact with the flat, intermediate portion of said strand, winding a first turn on said rod in the form of a helix having a pitch substantially equal to the width of the strand while maintaining the strand flat, winding the distal end of the strand in a series of overlapping, flat convolutions, progressing toward the distal end, and then winding the other end of the strand toward the scalp by rotating the rod and previously wound hair.

10. Permanent waving process including the steps of gripping a strand of hair adjacent the scalp, holding a curler rod transversely of and in

contact with a flat, intermediate portion of said strand, winding a first turn on said rod in the form of a helix having a pitch substantially equal to the width of the strand while maintaining the strand flat and of substantially constant width, 5 winding the distal end of the strand in a series of overlapping, flat convolutions, progressing toward the distal end, and then winding the other end of the strand toward the scalp by rotating the rod and previously wound hair.

11. Permanent waving process including the steps of gripping a strand of hair adjacent the scalp, holding a curler rod transversely of and in contact with a flat, intermediate portion of said strand, winding a first turn on said rod in the form of a helix having a pitch substantially equal to the width of the strand while maintaining the strand flat, winding the distal end of the strand in a series of overlapping, flat convolutions, 15 progressing toward the distal end, the strand being maintained of substantially constant width throughout, and then winding the other end of the strand toward the scalp by rotating the rod and previously wound hair.

12. Permanent waving process including the steps of holding a curler rod transversely of and in contact with a flat intermediate portion of a strand of hair, winding a first turn on said rod in the form of a helix having a pitch substantially equal to the width of the strand, winding a portion of the distal end of the strand in a series of overlapping, helical convolutions of substantially equal width and of smaller pitch than said first turn and then winding the inner end of the strand toward the scalp in Croquignole fashion, making use of a portion of the previously wound hair as a portion of the winding mandrel for the inner end of the strand.

13. Permanent waving process including the steps of holding a curler rod transversely of and in contact with a flat intermediate portion of a strand of hair, winding a first turn on said rod in the form of a helix having a pitch substantially equal to the width of the strand, winding a portion of the distal end of the strand in a series of overlapping, helical convolutions of substantially equal width and of smaller pitch than said first turn, interleaving a portion of sheet material with a terminal portion of the strand and winding it up therewith, and then winding the inner end of the strand toward the scalp in Croquignole fashion, making use of a portion of the previously wound hair as a portion of the winding mandrel for the inner end of the strand.

14. A separator for a terminal, wound portion of a flat hair strand comprising an elongated piece of flexible sheet material having a minor portion at one end stiffened to a greater extent than the major portion thereof.

15. A separator for a terminal, wound portion of a flat hair strand comprising an elongated piece of light weight, loosely woven fabric lightly coated with latex and having a minor portion at one end stiffened to a greater extent than the major portion thereof.

16. In combination, a curler rod having a central, axially extending bore, a guide rod rotatably and slidably received in said bore and hair wind-

ing means carried by said guide rod and having a portion provided with a cylindrical inner surface concentric with said guide rod, and interengaging means on said curler rod and said surface for predetermining the position of hair 5 wound on said curler rod by rotation of said winding means.

17. In combination, a curler rod having a central, axially extending bore, a guide rod rotatably and slidably received in said bore and hair winding means carried by said guide rod and having a portion provided with a cylindrical inner surface concentric with said guide rod, and interengaging means on said curler rod and said surface for predetermining the position of hair wound 10 on said curler rod by rotation of said winding means, said curler rod having a helical depression thereon and said interengaging means comprising a helical guide groove of substantially the same pitch as the helical depression on said 15 curler rod.

18. In combination, a curler rod, hair tensioning and guiding means, means supporting said first means for motion around and along said curler rod, said first means comprising an element 25 extending longitudinally of said curler rod and presenting a curved surface over which hair may be bent, a friction element adapted to urge the so bent hair against said curved surface and a comb-like element adapted to guide a flat 30 strand of hair between said elements.

19. Permanent waving process comprising the steps of winding a distal portion of a flat strand of hair, in flat formation, progressing toward the distal end from an intermediate point, interleaving 35 with a terminal portion of such distal portion of the strand a flexible sheet and winding it up therewith, then winding the scalp portion of said strand Croquignole fashion, heating such wound strand, with suitable waving solution, 40 whereby to impart a permanent wave thereto, and then unwinding such strand in reverse order as it was wound.

20. Permanent waving process comprising the steps of winding a distal portion of a flat strand 45 of hair, progressing toward the distal end from an intermediate point, interleaving with a terminal portion of such distal portion of the strand a flexible sheet and winding it up therewith, then winding the scalp portion of said strand 50 Croquignole fashion, heating such wound strand, with suitable waving solution, whereby to impart a permanent wave thereto, and then unwinding such strand in reverse order as it was wound.

21. Permanent waving process including the steps of holding a curler rod transversely of a flat strand of hair in contact therewith at a point intermediate the ends of such strand, clamping such strand to said curler rod at said point, winding the distal portion of such strand, while maintaining it flat and of substantially constant width, 55 on said curler rod toward the distal end of the strand, a first turn being laid down in the form of a helix of a pitch substantially equal to the width of the strand, and then winding up the 60 scalp portion of such strand Croquignole fashion.

FREDERICK K. BEZZENBERGER.
